UNITED STATES PATENT OFFICE.

SCHUYLER W. ZENT, OF EVANSVILLE, INDIANA, ASSIGNOR TO THE
ZENT AUTOMOBILE MANUFACTURING COMPANY, OF BELLE-
FONTAINE, OHIO.

DEVICE FOR EFFECTING THE RADIATION OF HEAT.

No. 805,510.

Specification of Letters Patent.

Patented Nov. 28, 1905.

Application filed March 16, 1904. Serial No. 198,509.

To all whom it may concern:

Be it known that I, SCHUYLER W. ZENT, a citizen of the United States, residing at Evansville, county of Vanderburgh, and State of Indiana, have invented certain new and useful Improvements in Devices for Effecting the Radiation of Heat, of which the following is a specification.

My invention relates to a method for effecting the rapid radiation of heat from objects exposed to a high temperature, and especially to reducing the temperature of internal-combustion cylinders.

My object is to provide such means for accomplishing this result as will combine lightness of weight with effectiveness. I accomplish this result by means of heat-conducting radiating-tubes, which are attached to and radiate from the surface of the cylinder. My invention is different from those now generally in use in that while the others seek to accomplish this object by simply acting as conductors of heat my invention embodies, in addition, the use of tubes constructed and disposed so that there is a constant draft of air through the tubes and over the surface of the cylinder.

In the drawings forming a part hereof, Figure 1 is a front view of one of my tubes. Fig. 2 is a side view of the same. Fig. 3 is a side view of one of my tubes in position on the cylinder. Fig. 4 is a transverse section of the cylinder on line X X of Fig. 3, showing my tube before it is secured in place or bent; and Fig. 5 is the same, showing my tube secured in position and bent.

In Fig. 1 my tube is illustrated, showing the hole A through same and the flaring end B at the bottom. At the bottom of the tube the metal end C is doubled over, thus providing extra metal for properly securing the tube in the aperture.

To apply my invention, I first make the proper dovetailed grooves D in the cylinder. These grooves may be extended either around the circumference of the cylinder or in any other direction I may desire. I then take my heat-conducting metal tubes and secure them in the grooves by tamping or pressing down the end C in such manner as to fill the groove and hold the tubes firmly in place. I then bend the tubes back, as shown in Figs. 3 and 5. This bending is done in such manner as

to allow the greatest possible current of air to pass through the tubes.

By the use of this invention I can place as many tubes in a cylinder as I desire and can bend them in any desired position.

While these tubes are made of heat-conducting metal and would therefore cause a great amount of heat to be radiated from the cylinder, their peculiar construction, embodying the flared lower ends, makes them far more effective and causes a constant draft from the cylinder to the surrounding atmosphere, the hole in the tube acting as does a flue.

Another advantage peculiar to this invention is that by having the lower end of the tube spread or flared I bring more heat-conducting metal into actual contact with the cylinder than do the tubes now in use, and this causes more heat to be radiated therefrom.

Having fully described my invention, what I claim as new, and desire to secure by Letters Patent, is—

1. In a device for effecting the radiation of heat, the combination with a surface, subject to heat effects, of open-ended heat-radiating tubes having one end flattened and broadened in a general crosswise direction thereof and secured by said end to the said surface.

2. In a device for effecting the radiation of heat, the combination with a surface, subject to heat effects, having recesses, of open-ended heat-radiating tubes having one end flattened and broadened in a general crosswise direction and secured by said end in said recesses.

3. In a device for effecting the radiation of heat, the combination with a surface, subject to heat effects, having recesses, of open-ended heat-radiating tubes having one end flattened and broadened in a general crosswise direction and received in said recesses and expanded or tamped therein to secure the tubes by filling the recesses.

4. In a device for effecting the radiation of heat, the combination with a surface, subject to heat effects, of heat-radiating tubes having one end slit and spread to provide an air-opening and secured to the said surface.

5. In a device for effecting the radiation of heat, the combination with a surface, subject to heat effects, having recesses, of heat-radiating tubes having flattened and bent ends received in said recesses and expanded therein.

6. In a device for effecting the radiation of

heat, the combination with a surface, subject to heat effects, having recesses, of heat-radiating tubes having slit open ends provided with flattened portions received in the recesses and 5 expanded therein.

7. In a device for effecting the radiation of heat, the combination with a surface, subject to heat effects, having undercut recesses, of open tubes having slit open ends provided

with flattened bent portions received in the 10 recesses and expanded therein.

In testimony whereof I hereunto affix my signature in the presence of two witnesses.

SCHUYLER W. ZENT.
